US00D834608S

(12) **United States Design Patent** (10) **Patent No.:** **US D834,608 S**
Cho (45) **Date of Patent:** **** Nov. 27, 2018**

(54) **DISPLAY SCREEN OR PORTION THEREOF WITH GRAPHICAL USER INTERFACE**

(71) Applicant: **Samsung Electronics Co., Ltd.,**
Suwon-si (KR)

(72) Inventor: **Min-kyung Cho**, Seoul (KR)

(73) Assignee: **SAMSUNG ELECTRONICS CO., LTD.**, Suwon-si (KR)

(**) Term: **15 Years**

(21) Appl. No.: **29/589,039**

(22) Filed: **Dec. 27, 2016**

Related U.S. Application Data

(63) Continuation of application No. 29/562,778, filed on Apr. 28, 2016, now Pat. No. Des. 778,313, which is a continuation of application No. 29/513,746, filed on Jan. 5, 2015, now Pat. No. Des. 758,416.

(30) **Foreign Application Priority Data**

Aug. 28, 2014 (KR) 30-2014-0042025

(51) **LOC (11) Cl.** **14-04**

(52) **U.S. Cl.**

CLAIM

The ornamental design for a display screen or portion thereof with graphical user interface, as shown and described.

DESCRIPTION

FIG. 1 is a front perspective view of a display screen or portion thereof with graphical user interface showing my new design;

FIG. 2 is a front view thereof; and,
FIG. 3 is a right-side view thereof.

The broken lines in the drawings show portions of the display screen or portion thereof and portions of the graphical user interface that form no part of the claimed design.
